UNITED STATES PATENT OFFICE.

JOHN HEISSENBERGER, OF NEW YORK, N. Y.

AUTOMATIC PICTURE-EXHIBITOR.

SPECIFICATION forming part of Letters Patent No. 624,801, dated May 9, 1899.

Application filed August 3, 1898. Serial No. 687,596. (No model.)

To all whom it may concern:

Be it known that I, JOHN HEISSENBERGER, of the city of New York, borough of Manhattan, in the county of New York and State of New York, have invented a new and useful Improvement in Automatic Picture-Exhibitors, of which the following is a full, clear, and exact description.

The object of the invention is to provide an automatic machine for exhibiting pictures in which the pictures will be illuminated and wherein the illumination of the pictures will be automatically commenced when the picture-carrier is first moved and will continue until all the pictures in the carrier have been brought opposite the eyepiece, after which the movement of the picture-carrier will be automatically stopped and the illumination automatically cut off.

A further object of the invention is to provide an automatic picture-exhibitor which will be coin-operated, the movements of the machine being controlled by a coin dropped into a pocket of a coin-receiving lever.

Another object of the invention is to construct a coin-receiving drawer which will serve to lock the casing of the machine to the base, and, further, to provide a coin-operated picture-exhibiting machine which will be exceedingly simple, durable, and economic in its construction.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the complete machine. Fig. 2 is a partly-sectional plan view substantially on the line 2 2 of Fig. 3. Fig. 3 is a vertical section taken substantially on the line 3 3 of Fig. 2. Fig. 4 is an enlarged

detail sectional view illustrating the coin-receiving lever in its normal position or in position to receive a coin and in position to stop the driving mechanism for the picture-carrier. Fig. 5 is a view similar to Fig. 4, the coin-receiving lever being shown partly in section and partly in positive lines, the lever being shown as in position to admit of the

movement of the picture-lever, the coin-pocket being shown as about to be opened, while in dotted lines the coin-receiving pocket is illustrated as having been opened and the driving mechanism for the carrier as stopped. Fig. 6 is a horizontal section through a cylindrical form of the machine in which the casing is entirely removable from the base, the section being taken just above the picture-carrying frame. Fig. 7 is a vertical section through a portion of the bottom of the machine shown in Fig. 6, illustrating the position of the coin-receiving drawer therein and the manner in which the said drawer locks the casing to the base of the machine; and Fig. 8 is a horizontal section showing the coin-receiving drawer in locked position, its guides, and the manner in which the locking connection is effected between the drawer and the casing of the machine.

In Figs. 1, 2, and 3 I have illustrated the casing A of the machine as being square or rectangular, the front upper portion 10 of the casing being inclined, as shown particularly in Figs. 1 and 3. At the central portion of the inclined section 10 of the casing an eyepiece 11 is secured, and the said eyepiece is in direct communication with a downwardly and rearwardly extending box 12, which box is provided at its inner end with a lens 13 of any desired character. One side of the box-casing A is preferably provided with a door in order that access may be readily attained to the interior of the said casing. Upon the top of the casing, at or near the center, a sign-board 13^a is located; but this sign-board may be omitted, if so desired. The lens 13 points directly to a space between diverging reflectors 14 and 15, consisting, preferably, of mirrors which are supported in frames 16 of any desired character, and the frames at their bottom portions are connected by a plate 17, preferably highly polished, so as to serve also as a reflector.

The frames containing the mirrors are connected with and are supported from the central back portion of the casing by means of a bracket 17^a of any desired character. The mirror-supporting-frame is open at the back, and consequently the brackets 17^a connect with the sides, and at the rear of the open back of the mirror-supporting frames and re-

moved a suitable distance therefrom a translucent pane 18 is supported in the front of the box 19, in which box an electric lamp of suitable candle-power is located or sustained.

5 The frame 19, in which the electric lamp is contained, is supported by a metal bracket 20, and this bracket is carried downward and is secured to a horizontal partition 21, which is shown as extending from one side of the casing, terminating short of the side at which the door is placed, and the said partition may extend from the front of the casing, but terminates short of its rear face in order that cells may be accommodated at the back portion of the casing, which cells rest, preferably, upon the floor of the casing and are held by suitable brackets *b* in an upright position. Any desired number of cells may be employed. In the drawings three cells are illustrated, 15 (designated, respectively, as B, B', and B².) The coupling of these cells relative to the electric lamp and other parts of the machine to be electrically operated will be hereinafter fully described. The partition 21 is supported 20 by suitable uprights or legs 22, which usually extend from the bottom of the casing; but brackets may be substituted for these legs if in practice it is found desirable.

At one side of the eyepiece 11 a coin-receiving slot 23 is made in the inclined portion 10 of the casing, and this coin-receiving slot is directly connected with a coin throat or chute 24, having an inclination downwardly and slightly to the rear, and the said chute is supported by one or more brackets 25, attached 25 to the front portion of the casing, as is particularly shown in Fig. 3. The back 26 of the chute is open, and at each edge of the open front a longitudinal flange is formed, adapted 30 to receive and guide a coin of predetermined dimensions—as, for example, a nickel. Any coin of less size will drop from the throat at the back and a coin of a larger size cannot be received by the throat. The lower end of the 35 chute is connected at the back by a strengthening-plate 27, which is more or less inclined and is adapted to assist in directing the coin into a pocket intended to receive it. A coin-operated lever, which is also adapted as a trip, 40 is fulcrumed by a horizontal stud 29 upon a suitable upright 28 or other support attached to the partition 21. One end of this lever is directly beneath the throat or coin-receiving chute 24, as shown in Figs. 2 and 3, and the 45 inner end of the coin-operated lever is provided with an adjustable weight 30, secured in desired position on the lever by a set-screw 31 or its equivalent, and the inner end of the lever is limited in its upward and downward 50 movement by upper and lower horizontal arms 32 and 33, (shown in Figs. 4 and 5,) which arms are attached to a standard 34, secured likewise to the partition 21. The forward end of the coin-operated lever, or the end which is 55 beneath the coin-receiving chute or throat 24, is provided with a pocket C', which pocket, as is particularly shown in Figs. 4 and 5, consists 60 of a body-section 35, which body-section comprises two sides *a* and a back *a'*, attached to the forward end of the said lever and having a downward and a rearward inclination, and a section 36, the said section comprising triangularly-shaped sides *a*² and a back *a*², the back being inclined downwardly and forwardly to meet the front *a'* of the forward section 35 of the pocket at the lower end of said section, as shown in positive lines in Fig. 5. The wider portions of the sides of the section 36 of the pocket are at the top, and these side portions of the section 36 of the pocket are pivoted to the sides of the fixed section 35 by pins 37 or their equivalents, located near the front edges of the side portions of the rear section of the pocket, as is also shown in Figs. 4 and 5, and the two sections of the pocket are held closed at the bottom by a spring 38 or its equivalent, which has bearing against the back of the pivoted section of the pocket and a rigid attachment to the coin-operated lever C. A trip-arm 39 of angular construction is attached to the rear face of the pivoted section of the pocket, and the free end of the trip-arm 39 is in the path of a tappet 40, which is secured upon a wheel 41, which wheel is driven through the medium of a motor D, which motor is preferably a clockwork-motor and is supported by the partition 21, the governor or fan of the said motor being designated as 42. A contact-arm 43 is projected downward from the coin-operated lever, and the said contact-arm is adapted to operate a circuit-closer. The lower end of the contact-arm 43 is preferably provided with a covering 44 of an insulating material, and the circuit-closer consists of two opposing members 45 and 46, preferably made from copper, the member 45 being attached to a metallic plate 45^a at its outer end, the said plate being secured to the partition 21, while the member 46 is secured to a plate 46^a at its outer end, 100 likewise fastened to the partition 21, as shown in Fig. 2. The member 45, which is adjacent to the contact-arm 43, is shown as provided with a flange 45^b, adapted when the member 45 is forced in direction of the member 46 to 105 engage with a return end 46^b on the said member 46, thus effecting a contact between the two members, and when such a contact is effected and during the contact the current 110 will be turned on the lamp contained in the 115 casing 19.

A stop is employed for the motor D, and the said stop is in the form of an arm which is projected from the coin-operated lever C, usually at a point between its pivot and its 120 weighted end, the said arm 47 being carried in such direction that it will cross a blade of the governor 42 when the coin-operated lever is in its normal position and prevent the governor from turning, as illustrated in Fig. 4; 125 but when a coin is in the coin-receiving receptacle C' the stop-arm 47 will be carried out of the path of the governor 42 and the motor will be free to operate. The wheel 41, 130

carried by the motor D, is a time-wheel and is provided with a series of recesses 48, radially produced in its peripheral surface, and, preferably, one side wall of each recess is beveled, as shown in dotted lines in Fig. 5.

In connection with the time-wheel 41 a picture-carrier E is employed. This picture-carrier is preferably of circular formation, and its sides are made to taper, the carrier being of greater diameter at the top than at the bottom. In the usual construction of the carrier an upper band 49 is provided, together with a lower band 50, and these bands are connected, at regular intervals by vertical braces 51. These braces are preferably given the form of two opposing plates 51^a and 51^b, the plates 51^a being the outer plates and the plates 51^b the inner plates, as shown in Fig. 2. The inner plates 51^b are bent laterally in opposite directions from their longitudinal centers, forming between the two plates, at each side of the center, slideways 52, the said slideways being adapted to receive the pictures, which are produced upon transparent panels 53. The number of panels in the picture-carrier corresponds to the number of slots 48 in the time-wheel 41.

In the further construction of the time-wheel a horizontal spoke 54 is carried from the center of each of the upright braces 51 to a connection with a central plate 55, and at each spoke 54 a pendant is located, which pendants are usually in the form of pins 56, as illustrated. The time-wheel will hold the picture-carrying wheel a sufficient length of time, until the said carrying-wheel is turned by the motor D, for example, from the first to the second slot therein, which slot allows the downwardly-projecting pin to pass through, and the following pin of the picture-carrying wheel will be held by the time-wheel until the picture-carrying wheel has again turned to present the next slot. This operation will hold one picture after another a desired length of time before the eyepiece, or wherever the picture is to be directly viewed; but when the motor D is stopped one of the pins will engage the time-wheel between two adjacent slots, as is clearly shown in Fig. 4.

50 The picture-carrier is mounted to revolve between the mirror-carrying frame and the translucent illuminating-pane 18, as shown best in Fig. 3, and preferably the picture-carrying frame is provided with a hub 57, and the said hub is secured to the shaft 58 of a second motor D', which latter motor will operate the moment that the time-wheel is turned to admit of the passage of the pins 56 through the slots in the said wheel.

55 Just below the coin-receiving receptacle C' an inclined plate 59 is preferably located, which serves to direct the coin dropped from the said receptacle into a drawer or a box 60, located in the bottom of the casing, and this drawer or box may be readily removed when the door 61 of the casing is opened, which door is best shown in Fig. 2. The coupling

of the batteries B, B', and B² with the electric lamp and circuit-closer may be made as shown in the drawings, in which in detail the positive element 62 of the battery B² is connected with a plate 63, located on the partition 21, the negative element 65 of the battery being connected by a wire 66 with the positive element 67 of the battery B, and the negative element of the battery B is connected with the positive element of the battery B' by a wire 68. A wire 69 is carried from the plate 63 to the lamp and the metal bracket 20, supporting the lamp, while a wire 71 is carried from the negative element 70 of the battery B' to the plate 46^a, connected with the member 46 of the circuit-closer, the plate 45^a of the member 45 of the circuit-closer being connected with the base of the bracket 20 by a wire 72 and through said bracket to the lamp. Wires 73 and 74 are carried from the plates 45^a and 46^a to a push-button 75, located, preferably, at the top portion of the casing. In Fig. 1 the battery is designated as x, and the connection between the battery, one member of the circuit-closer, and the push-button is designated as x', the connection between the lamp, the other member of the circuit-closer, and the push-button being designated 90 as x².

I desire it to be understood that while the electrical connections are usually made as shown and described the wiring may be made in any manner known to persons experienced in such work.

In the operation of this form of the device one of the transparent panels in the picture-carrier will always be opposite the illuminating-pane 18, and by manipulating the push-button the circuit will be closed and the light turned on, enabling a person to see the first picture without charge. When a coin of suitable denomination is dropped into the coin-chute 24, it will fall into the receptacle C' and will carry that end of the coin-operated lever C downward to the position shown in Fig. 5, whereupon the stop-arm 47 will be removed from the path of the governor 42 of the motor D, enabling the said motor to work. This motor will now revolve the time-wheel, and whenever an opening in the time-wheel is brought in position to admit the passage through the opening of a pin 56, projected through the picture-carrier, the picture-carrier will turn a sufficient distance to bring another picture-panel opposite the illuminating-panel 18 or the panel back of which the lamp is located. This panel will remain in the line of vision until the time-wheel has turned a sufficient distance to bring the pin which engaged with the time-wheel when the picture was shifted opposite a second opening in the time-wheel, whereupon the picture-carrier will revolve a sufficient distance to bring another picture within the line of vision, and the next pin will strike the time-wheel and prevent the carrier from turning farther until an opportunity has offered for the re-

lease of the pin. As soon as the coin drops into the coin-receptacle the contact-arm 43, connected with the coin-operated lever, will be forced against the member 45 of the circuit-closer, bringing it in contact with the opposing member 46, completing the circuit and illuminating the lamp.

In the form of the device shown in Figs. 6, 7, and 8 the base F is circular, as is likewise the casing F'. In fitting the casing to the base the casing is made to enter an annular groove 83 in the base, as shown particularly in Fig. 7. A partition or platform 76 is located above the base corresponding to the partition 21, and this partition is held in position by uprights 77, which are carried above the partition almost to the top of the casing and extend inwardly over the picture-carrier E, but out of contact therewith. One of the uprights is adapted to carry contacts 78 for the push-button which is located in the top of the casing, and two other of the uprights 77 are adapted to support the frames 16, that hold the mirrors 15, the mirrors and frames being the same as those described in the other form of the device, except that the bottom connecting-piece of the frames is omitted, and these frames are held within the picture-carrier, as before stated, in front of the lamp-casing already described. The picture-carrier is operated through the medium of a motor D', the same as that heretofore described, and in connection with the motor D' a second motor D is employed, the same as that heretofore described and carrying a similar time-wheel 41 and governor 42. The coin-operated lever C, which is practically of the same construction as in the other form of the device, is provided at one of its ends with a coin-receptacle C', similar to that heretofore described and similarly operated; but below the coin-receiving receptacle a chute 77^a is provided, having a downward and inward inclination to an opening 78^a, made in the partition 76. The same form of circuit-closer is employed, operated in the same manner as heretofore described; but the circuit-closer is shown surrounded by a boxing 79, which when covered has an opening to admit of the movement of the contact-arm 43 of the coin-operated lever. The pivot-pin 29 of the coin-operated lever, however, is in this instance preferably projected from the casing of the motor D', and instead of the guides 32 and 33 employed in the other form of the device to regulate the upward and downward movement of the coin-operated lever an arm 80 is projected from each side of the pivot-point 29 of the said lever, and an outwardly-extending member 81 is provided at one end of the said arm, while a lower member 82 is carried in like direction from the opposite end of the arm 80, the arm 81 serving as a rest for the coin-operated lever when in its normal position and the member 82 acting as a rest for the said lever when it is inclined or when a coin is in the receptacle C'.

Any desired number of batteries G are employed, and these batteries are connected in any suitable or approved manner with the filament of the electric lamp used, the circuit-closer, and the push-button. In fact, the electric connection may be made with the aforesaid points in substantially the same manner as has been heretofore described. In all cases the batteries used are preferably dry batteries.

Guides 84 are secured to the base F of the device below the opening 78^a in the partition or platform 76, the said guides being provided at a suitable distance from their forward ends with offsets 85, that extend to the rear ends of said guides. An opening 86 is made in the casing F' at the front, and immediately at the rear of the opening in the casing horizontal lugs 87 are formed, as shown in Fig. 8. The drawer 88, adapted to receive coin, is entered at the opening 86 in the casing, and the said drawer is provided with rods 89 at its sides, or said rods may be projected from its ends, the rods being adapted to enter the guides 84, and after the drawer has been entered into the opening 86 of the casing sufficiently to close the said opening the rods 89 will have passed through the guides 84 and over the lugs 87 at the opposite side of the casing. In this manner the money-drawer into which the coin is guided by the chute 77^a serves to lock the casing to the base. The drawer is provided with any suitable form of lock, preferably a lock operated by a key 90, as shown in Figs. 7 and 8.

I desire it to be understood that the picture-carrying wheel may be made flat and the negative or picture secured therein in such manner that the view of the negative or picture may be thrown upon a screen. Under such a construction substantially the same arrangement of motors and controlling devices may be employed.

Having thus described my invention, I claim as new and desire to secure by Letters Patent—

1. In a coin-operated picture-exhibitor, a rotary picture-carrier, a motor for operating the same, a time-wheel, a motor for the time-wheel, a coin-receiving lever, the motor for the time-wheel being stopped and started by the movement of the coin-receiving lever, and means carried by the picture-carrier and adapted to engage the time-wheel to hold the picture-carrier stationary and to be released from the time-wheel to permit the picture-carrier to move, as set forth.

2. In a coin-operated picture-exhibitor, a picture-carrier and two coöperating motors, one of said motors being arranged for driving the picture-carrier and the other motor being provided with a time-wheel having peripheral slots for the passage of projections on the picture-carrier, the said time-wheel controlling the length of time a picture is to be exhibited, and a coin-operated lever arranged to stop and start the motor, as set forth.

3. In a coin-operated picture-exhibitor, a rotatable picture-carrier provided with pendants, a motor for the same, an incandescent lamp arranged to illuminate the pictures, an electric circuit within which the lamp is contained, a time-wheel having slots in its periphery for the passage of the pendants, a motor for the time-wheel, and a coin-receiving lever arranged to stop or start the motor and make or break the circuit for the lamp, as and for the purpose specified.
4. In a coin-operated picture-exhibitor, a rotatable picture-carrier provided with projections, an incandescent lamp arranged at the rear of the said carrier, reflectors located within the said carrier at opposite sides of the incandescent lamp, an electric circuit within which the lamp is contained, a motor for the carrier, a time-wheel provided with peripheral slots for the passage of the projections from the carrier, and a coin-receiving lever arranged to stop and to start the motor and make or break the circuit for the lamp, substantially as described.
5. In a coin-operated picture-exhibitor, a rotatable picture-carrier of greater diameter at the top than at the bottom, the said picture-carrier being provided with slideways adapted to receive transparent panels containing pictures, an incandescent lamp arranged to illuminate the pictures, said lamp being located at the exterior of the carrier, and reflectors at each side of the lamp, located within the picture-carrier, the lamp and reflectors being stationary, an electric circuit within which the lamp is contained, a motor for the carrier, and a coin-receiving lever arranged to stop or start the motor and make or break the circuit for the lamp, as and for the purpose specified.
6. In a picture-exhibitor, a revolute picture-carrier, an illuminating device for the pictures, a motor for the picture-carrier, a time-wheel having peripheral slots for the passage of projections on the carrier, a motor for the time-wheel and a coin-receiving lever provided with a projecting arm serving as a stop for the motor, substantially as described.
7. In a picture-exhibitor a revolute picture-carrier, an electric illuminating apparatus for the pictures, a motor-operated time-wheel provided with openings for the passage of projections on the picture-carrier and controlling the display of the picture-carrier, a coin-operated lever, and a tappet carried by the time-wheel and controlling said lever, the said lever being arranged to stop and start the motor, as specified.
8. In a picture-exhibitor a revolute picture-carrier, an electric illuminating apparatus for the pictures, a circuit in which the illuminating device is located, a circuit-closer located within the said circuit, a motor-operated time-wheel engaging and releasing the picture-carrier and controlling the display of the pictures, a coin-operated lever controlled

by the time-wheel and arranged to stop and start the motors, and a contact-arm projected from the said coin-lever and adapted to operate the circuit-closer substantially as described.

9. In a picture-exhibitor, a motor-controlled picture-carrier, an electric light, a circuit for the light including the battery, the light being arranged to illuminate the pictures in the said carrier, a time mechanism controlling the display movement of the carrier and comprising a motor having a governor, and a time-wheel carried by the motor and engaging and releasing the picture-carrier, a coin-operated lever, a trip carried by the time-wheel and arranged for engagement with an arm on the lever, and a stop for the motor controlling the time mechanism and comprising an arm projected from the coin-operated lever and adapted to engage the governor of the motor, substantially as described.

10. In a picture-exhibitor, a motor-controlled picture-carrier adapted to revolve, the said carrier being provided with pendants located between the panels containing the pictures, a motor-operated time-wheel having peripheral slots for the passage of the pendants from the picture-carrier, a coin-operated lever provided with an extension, arranged to be tripped by the movement of the time-wheel, and a second extension arranged to stop the movement of the lever after the trip connection of the time-wheel with said lever, as described.

11. In a picture-exhibitor, a motor-controlled picture-carrier provided with pendants located between the panels in the said carrier containing the pictures, a motor-operated time-wheel having peripheral slots for the passage of the pendants from the picture-carrier, a coin-operated lever provided with an extension arranged to be tripped by the movement of the time-wheel, a second extension from the lever arranged to stop the movement of the lever after the trip connection of the time-wheel with the said lever, an electric light arranged to illuminate the pictures, and a circuit including a battery, in which circuit the light is contained, the said circuit being opened and closed by the movement of the said lever, for the purpose set forth.

12. In a picture-exhibitor, the combination, with a motor-operated picture-carrier, the said carrier being adapted to revolve, and a motor-operated time-wheel provided with peripheral slots, the slots corresponding in number to the number of pictures in the carrier, of a coin-operated lever, a tappet carried by the time-wheel, and an extension from the lever arranged in one position of the lever to be engaged by the tappet of the time-wheel, and a second extension from the said lever arranged to stop the motor after the lever has been operated upon by the said time-wheel and the coin discharged from the lever, for the purpose specified.

13. In a picture-exhibitor, the combination, with a revolvel picture-carrier, a motor arranged to drive the same, a second motor, a time-wheel carried by the second motor, and having peripheral openings corresponding in number to the number of pictures, and projections from the carrier adapted to engage with the time-wheel and also to pass through the openings therein, of an electric lamp, a circuit including the battery for the said lamp, a coin-operated lever provided with a coin-receptacle, consisting of pivotally-connected members, means for opening and closing the circuit by the movement of the said lever, and means, substantially as described, for releasing a coin from the coin-receptacle of the lever by the movement of the time-wheel, as specified.
14. In a picture-exhibitor, the combination, with a motor-operated picture-carrier provided with guides for the reception of transparent picture-carrying panels, a stationary illuminating device located outside of the carrier, reflectors located within the carrier at opposite sides of the illuminating device, and a second motor provided with a governor and a time-wheel having peripheral slots corresponding in number to the number of pictures in the carrier, of a lever, means for limiting the movement of the said lever, a coin-receiving receptacle carried by the said lever, the said receptacle being provided with a spring-controlled movable section, capable in one position of discharging the coin deposited in the said receptacle, a trip connection between the movable section of the coin-receiving receptacle and the time-wheel, batteries, a circuit connection between the batteries and the illuminating device, a circuit-closer being located within the said circuit, means, substantially as described, for operating the circuit-closer by the movement of the lever, and a projection from the lever adapted in one position of the lever to engage with the governor

of the motor carrying the time-wheel, all arranged substantially as herein described. 45
15. In a picture-exhibitor, a motor-controlled picture-carrier adapted to revolve, a motor-operated time-wheel controlling the movement of the picture-carrier, a coin-operated lever provided with an extension arranged to be tripped by the movement of the time-wheel, and a second extension arranged to stop the movement of the lever after the trip connection of the time-wheel with said lever, substantially as described. 50
16. In a coin-operated picture-exhibitor, a rotatable picture-carrier, a motor for the same, an incandescent lamp arranged to illuminate the pictures, an electric circuit within which the lamp is contained, a circuit-closer located within the said circuit, a time-wheel adapted to engage and release the picture-carrier, a motor for the time-wheel provided with a governor, and a coin-receiving lever 65 provided with an arm adapted in one position of the lever to engage with the governor of the motor, the said lever being also provided with a contact-arm adapted in another position of the lever, to operate the circuit-closer, substantially as described. 70

17. In a picture-exhibitor a rotatable picture-carrier of greater diameter at the top than at the bottom, the said picture-carrier being provided with slideways adapted to receive 75 panels containing pictures, an illuminating device located outside of the carrier, reflectors at each side of the illuminating device and located within the picture-carrier, the illuminating device and reflectors being stationary, a motor for the picture-carrier, and a coin-receiving lever, arranged to stop and start the motor, for the purpose specified. 80

JOHN HEISSENBERGER.
